US0D1070082S

(12) **United States Design Patent** (10) **Patent No.:** **US D1,070,082 S**
(45) **Date of Patent:** **** Apr. 8, 2025**

(54) **ENDOSCOPE HANDLE**

- (71) Applicant: **AdaptivEndo LLC**, Louisville, KY (US)
- (72) Inventors: **Michael W. Goldenbogen**, Xenia, OH (US); **Gregory R. Furnish**, Louisville, KY (US)
- (73) Assignee: **AdaptivEndo LLC**, Louisville, KY (US)
- (**) Term: **15 Years**
- (21) Appl. No.: **29/789,350**
- (22) Filed: **Sep. 17, 2021**

Related U.S. Application Data

- (63) Continuation-in-part of application No. 29/781,304, filed on Apr. 29, 2021, now Pat. No. Des. 1,031,035.

(57) **CLAIM**

The ornamental design for an endoscope handle as shown and described.

DESCRIPTION

FIG. 1 is a front, right, perspective view showing my new design in a first embodiment;

FIG. 2 is a back, left perspective view thereof;

FIG. 3 is a left side elevation view thereof;

FIG. 4 is a back elevation view thereof;

FIG. 5 is a right side elevation view thereof;

FIG. 6 is a front elevation view thereof;

FIG. 7 is a top view thereof;

FIG. 8 is a bottom view thereof;

FIG. 9 is a front, right, perspective view showing my new design in a second embodiment;

FIG. 10 is a back, left perspective view thereof;

FIG. 11 is a left side elevation view thereof;

FIG. 12 is a back elevation view thereof;

FIG. 13 is a right side elevation view thereof;

FIG. 14 is a front elevation view thereof;

FIG. 15 is a top view thereof; and,

FIG. 16 is a bottom view thereof.

The broken lines illustrate portions of the endoscope handle or environmental structure and form no part of the claimed design.

1 Claim, 16 Drawing Sheets
